United States Patent

Des. 241,483
Patented Sept. 14, 1976

241,483

ELECTRIC SHAVER

Robert A. Chieda, Westport, Conn., assignor to Sperry
Rand Corporation, Bridgeport, Conn.

Filed Feb. 24, 1975, Ser. No. 552,632

Term of patent 14 years

Int. Cl. D28—03

U.S. CL. D95—3 A

Fig. 1.

Fig. 2.

Fig. 3.

FIG. 1 is a perspective view of the front and left side of an electric shaver showing my new design;

FIG. 2 is a top plan view of the shaver appearing in FIG. 1;

FIG. 3 is a bottom plan view of the shaver as seen in FIG. 4;

FIG. 4 is an elevational view of the front of the shaver of FIG. 1;

FIG. 5 is an elevational view of the right side of the shaver of FIG. 1; and

FIG. 6 is an elevational view of the rear of the shaver of FIG. 1.

In FIGS. 4 and 6 it is understood that the cutter teeth omitted for convenience of illustration are continuous in the paths indicated by dash-dot lines.

I claim:

The ornamental design for an electric shaver, substantially as shown and described.
